UNITED STATES PATENT OFFICE.

SAMUEL W. AVIS, OF HARTFORD, CONNECTICUT, ASSIGNOR TO THE MERROW MACHINE COMPANY, OF HARTFORD, CONNECTICUT, A CORPORATION OF CONNECTICUT.

FABRIC-GUIDE.

1,206,974.

Specification of Letters Patent.

Patented Dec. 5, 1916.

Application filed August 1, 1914. Serial No. 854,515.

To all whom it may concern:

Be it known that I, SAMUEL W. AVIS, a citizen of the United States, residing at Hartford, in the county of Hartford, State 5 of Connecticut, have invented certain new and useful Improvements in Fabric-Guides; and I do declare the following to be a full, clear, and exact description of the same, reference being had to the accompanying 10 drawings, forming a part of this specification, and to the characters of reference thereon.

My invention relates to sewing machines and objects of the said invention are: to 15 provide an apparatus whereby material to be operated upon by the stitch forming mechanism of a sewing machine may be presented to the said mechanism in an improved manner; to provide apparatus 20 whereby an overseam stitch may be applied to loosely woven fabric, knitted goods or any soft material in an improved manner; and to provide improved devices whereby the edges of knit goods and the like may be 25 joined by an overseam with greater ease and with more perfect results than heretofore.

The above and other objects of this invention will hereinafter become apparent.

In the drawings: Figure 1 is an elevation 30 of a machine embodying features of my invention. Sufficient of the machine is shown to illustrate the manner in which my invention is applied. Fig. 2 is a plan view (*i. e.* looking from the top of the Fig. 1) of 35 the embodiment of my invention shown, together with some parts of the machine. Fig. 3 is a view similar to Fig. 2 and in the same elevation, including some of the elements shown in Fig. 2 and showing a piece

40 of fabric being operated upon. Fig. 4 is a section taken on the line 4—4 of Fig. 2, looking in the direction of the feed and showing two layers of fabric in position. Figs. 5 and 6 are views of the compression 45 block alone, Fig. 6 being an elevation of the said block opposite to that elevation in which the block is shown in Fig. 1, and Fig. 5 being a plan view of the Fig. 6. Figs. 7 and 8 are views of the measuring 50 guide alone, the Fig. 7 being an elevation of the said guide opposite to that elevation in which the guide is shown in Fig. 1, and Fig. 8 being a plan view of the Fig. 7.

Throughout the drawings, like characters

of reference denote the same elements or 55 members.

The particular embodiment of my invention shown in the drawings is a form, which although particularly designed for selvage-seaming knitted fabrics, is suitable for a 60 variety of purposes involving the application of an overseam stitch to the edge of one or more layers of material. This embodiment I have shown applied to a two thread overseaming machine of the well known 65 Merrow type, wherein: the numeral 1 denotes the usual eye pointed needle, 2 denotes the usual looper and 3 denotes the usual loop carrier; the entire stitch forming mechanism being and operating sub- 70 substantially as set forth in United States patent to William H. Stedman No. 732,457, issued June 30, 1903.

The numeral 5 indicates the machine frame, 5^a the frame head, 6 a support for 75 the needle plate, 7 the forward feed dog and 8 the rear feed dog. The construction of the sewing machine represented, including the various mechanisms comprising a machine of this type and the operation of 80 the whole, where not involving the novel features of this invention or where not interfering with the proper functioning thereof, may be substantially as set forth in United States patents to William H. 85 Stedman No. 1,071,818, issued September 2, 1913; and Joseph M. Merrow No. 1,074,968, issued October 7, 1913.

Referring now more particularly to my invention as herein shown embodied and applied, the numeral 10 denotes a needle plate which is adapted to be secured to the support 6 by the screws 11.

The numeral 20 denotes the presser foot which is preferably provided with an extra 95 wide and large sole 21 and an extra long and high toe 22. This presser foot is carried by the frame head 5^a in the usual manner by means of the shank 23. On the laterally extending portion of the needle plate, *i. e.* on a portion of the needle plate extending out beyond the edge of the fabric, I place an edge compressing member denoted as a whole by the numeral 30. This compressing member is provided with the fabric compressing wall 31 which is arranged vertically, in a plane parallel to the rising and falling movement of the presser foot and

in a plane inclined laterally with respect to the direction in which the fabric is fed, the said wall inclining from a point outside and beyond the edge of the fabric toward the edge of the fabric and the line of sewing as the said wall 31 extends in the direction of the feed, as is well shown in Figs. 2 and 3. At the terminus of the wall 31, and preferably just abreast of the needle 1, the compressing member 30 is provided with a short retaining wall 32 which wall is preferably arranged in a plane parallel to a plane in which the path of the needle and the line of the direction of the feed will simultaneously lie. The wall 32 terminates with a rounded edge 33 and the upper corner 34 of the wall 32 is preferably rounded as is shown in Fig. 1. The member 30 is secured to the upper side of the needle plate 10 by means of a shank 35 having an elongated slot 36 therethrough, the side 36^a of which is parallel to the side 37 of the shank 35, and through which slot passes the screw 38, which screw is threaded into the needle plate 10, as is best shown in Fig. 4. The said member 30 is thus laterally adjustable with relation to the line of the direction of the feed, and the proper positioning and alignment of the said member is maintained throughout all of its lateral adjustments by the constraint effected through the engagement of the screw body 38^a with the side 36^a of the slot 36 and the engagement of the side 37 of the shank 35 with the side 41 of the shank 42 of the measuring guide, which guide is denoted as a whole by the numeral 40; since the shank 42 is slidably constrained and guided by the projection 43 which projection enters and engages the spline 12 in the needle plate 10. In the shank 42 of the measuring guide 40 is a slot 47 similar to the slot 36 through which slot passes the screw 44, which screw is threaded into the needle plate 10, whereby the said measuring guide is secured to the needle plate and is adjustable laterally with relation to the line of feed. The measuring guide 40 presents a fabric engaging wall 45 which wall is arranged substantially parallel to the line of feed and which is usually parallel throughout with the wall 32. The front edge 46 and the upper corner 46^a thereof, are preferably rounded as is shown in the drawings.

To the upper side of the foot of the presser foot 20 is secured a compression block denoted as a whole by the numeral 50. This block is secured to the presser foot by means of a shank 51 having an elongated slot 52 through which passes the screw 53, which screw is threaded into the foot of the presser foot. The block is laterally adjustable with respect to the line of feed and is slidably constrained and held in proper alignment with respect to the member 30 by means of the projection 54 which projection

enters and engages the spline 25 in the presser foot. The block 50 is provided with the depending compressing head 55 having a fabric or compressing surface 56 the forward face 57, or that face or portion that the fabric approaches and first engages, being upwardly inclined or generously rounded at the bow as is shown at 57^a. The surface 56 is preferably disposed in a plane coincident with the plane of the presser foot sole and the depending head 55 is designed to be interposed between the side or edge 26 of the presser foot and the wall 31 of the compressing guide 30, with the wall 58 always in intimate engagement with the wall 31. The side 26 of the presser foot and the wall 59 of the block should abut when the block is in its extreme inner or left hand position of adjustment and the wall 58 and the side or edge 27 of the presser foot should be in line and should also both engage the wall 31 when the said elements 58 and 27 are in the said relative positions due to the element 58 being in its extreme inner position of adjustment.

The numerals 13 and 14 denote the slots in the needle plate 10 that are provided, for the front and rear feed dogs respectively. The feed surfaces are preferably provided and located as shown and sometimes it is desirable to provide or apply additional feeding surfaces, all as hereinafter explained. The needle plate is also provided with an unusually long, slender and only slightly tapering chaining finger 15, as best shown in Fig. 2 and as hereinafter more fully explained.

I will now describe more particularly the manner of using the apparatus shown and described and the improved manner in which an overedge seam or finish may be applied to a fabric, using the joining of two pieces or layers of ribbed knit goods or sweater material (represented in the Figs. 3 and 4 and denoted by the characters F and F') by a series of two thread overseam stitches to form an overedge seam, (as shown in the upper right hand portion of the Fig. 3, the seam being denoted as a whole by the character S,) as an illustration, and assuming at the outset that the apparatus be adjusted substantially as shown in the drawings. The fabric, F and F', is placed between the presser-foot and the forward feed dog 7 in the usual manner with the edges f and f' engaging the wall 45 of the measuring guide 40. The feed dog 7 grasps the fabric and feeds the same to the needle 1 in the usual manner. As the fabric approaches the needle in the usual manner, the sides of the edges f and f' of the said fabric encounter the wall 31 of the compressing member 30 as shown in Figs. 3 and 4 and, due to the motion imparted to the fabric by the feed, the direction of which motion is indicated by the arrow in Fig. 3, the edges f

and f' of the fabric are forced laterally, to the left as viewed in Figs. 3 and 4, and, since the fabric is clamped firmly between the ample feeding surface and the presser foot sole, 5 thus being held against lateral movement, ordinarily, only that portion of the fabric lying between the line of the feed dog 7 and the plane of the wall 45 of the guide 40 will be affected when the edges f , f' of the fabric are crowded to the left by the wall 31 as may be seen from Fig. 3.

At or about the same time that the wall 31 begins to crowd the fabric edges to the left, the top of the edge " f " encounters the 15 inclined or rounded portion 57^a of the compression block 50 (which the fabric approaches from the left as viewed in Fig. 6) whereby the edges of the fabric are crowded under the surface 56 and between the surface 20 56 and the upper side of the needle plate. Therefore, since the fabric is held against being moved to the right by the action of the wall 31 on the edges thereof, and since the edges f and f' are prevented from 25 bulging by the constraint effected between the surface 56 and the upper side of the needle plate or, if they have already begun to bulge they are again crowded down under the surface 56 by the portion 57, it is 30 apparent that the structure of the fabric must become compressed, and that the said structure of the fabric will be compressed chiefly laterally *i. e.* to the left, as shown in Fig. 3. In other words the upper face of 35 needle plate 10, the wall 31, and surface 56 of compression block 50, form a channel through which the fabric edges pass as the fabric is advanced by the feed dogs. This channel, from its mouth to its termination 40 adjacent to the point of stitch formation is tapered or gradually constricted so that during advancing movement of the fabric, the edges thereof are compacted progressively until the maximum compression is effected 45 just in advance of the point at which the securing stitches are applied.

When the feeding movement of the fabric has stopped and the feeding surface has 50 dropped below the needle plate, the ample surface of the presser foot sole clamps the fabric down on the upper surface of the needle plate and holds the fabric in the compressed condition in which the said fabric exists when the feed becomes disengaged 55 therefrom. The feed and the presser foot, and, the presser foot and the needle plate continue to coöperate with the members 30, 40 and 50 in the manner set forth, the feed 60 and presser foot operating to feed the fabric in a direction inclined to the longitudinal extent of the wall 31, and the presser foot and needle plate operating to hold the fabric during the intervening time between the 65 feeding movements; the fabric becoming more and more compressed until, reaching

the retaining wall 32 abreast of the point of needle penetration in a state of maximum lateral compression, the fabric is presented to the needle. The needle then coöperates with the stitch forming implements 2 and 3 in the usual manner to form an overseam stitch that passes through a point in the compressed fabric and around the edge of the said compressed fabric and the chaining finger 15 simultaneously while the fabric is encompassed by the said stitch is still in its compressed state. This operation is continuously repeated in the formation of a seam, such as is represented by S in Fig. 3, the compressed fabric edges being held together 70 and bound by a stitch such as is represented in Fig. 3 and indicated by the characters N and L, (the former indicating the needle loop and the latter the looper loop) before the said edges leave the end 33 of the retaining wall 32. Since the formed stitches, while still surrounding the chaining finger and the fabric, are relied upon, to some extent to assist in the holding of the compressed fabric edge against the retaining wall 32, and since it is desired that the stitches, after being tied down on the still compressed fabric and the chaining finger, be loosened as little as possible when dropped by the said 75 chaining finger, and since it is desirable also, that the stitches be not shed too fast, a comparatively long, slender and only slightly tapering chaining finger is particularly desirable in connection with the present apparatus and therefore such a finger is preferably provided.

The Fig. 3 is intended to illustrate the improved manner in which an edge to be overseamed is first prepared and the manner in which the overseam is then applied. In the illustrated example, for the sake of clearness, a rather wide seam is represented. In this case the rib " r " of the fabric, the grooved portion " g " and the rib " r' " are shown compressed until at the point of needle penetration, the two ribs and the grooved portion have become narrower than the normal width of the rib r' . The stitch is formed over the fabric while thus compressed, the needle preferably penetrating the center of the rib r' and the resulting seam S, is in this case represented as being only about half the width of a seam formed over the same amount of fabric in the ordinary well known manner without the use of my invention, although far greater reduction is often effected. To secure a narrower seam, the member 30 is adjusted to set the retaining wall 32 closer to the needle, the said wall 32 in some adjusted positions being adapted to prevent any undue deflection of the needle. As has been hereinabove stated, whenever the member 30 is adjusted, the member 50 must be adjusted accordingly. When greater compression of 80 85 90 95 100 105 110 115 120 125 130

the fabric is desired, the lateral distance between the walls 32 and 45 is increased and when less compression is desired, the lateral distance therebetween is diminished, 5 *i. e.* the farther the plane of the wall 45 lies to the right of the plane of the wall 32, as viewed in Figs. 2 and 3, the greater will be the compression and, vice versa.

With the use of the apparatus of my invention, an extremely narrow, very strong and close seam may be produced in an improved manner, the resulting seam being soft, flexible, ridgeless and practically invisible when the fabric is opened out flat, 10 15 the line of junction of the fabric being very difficult to distinguish from the adjacent fabric. Another matter of importance is, that fabric is more easily covered or joined than heretofore, *e. g.* in the case of joining 20 two edges of sweater material, it is not so serious a matter if the two edges are somewhat uneven or do not properly register, for, provided that the variation does not too much exceed the lateral distance between 25 the walls 32 and 45, the edges will be sure to be caught by the needle, and in many cases of fabric with ragged edges or fabric having gaps or bad spots in the edges, if the case be not too extreme, the edges may 30 be strongly sewed and well covered for either joining or finishing, by suitably adjusting the apparatus. It is obvious that goods may also be sewed across the wale.

While the adjustment of the apparatus 35 shown depends largely upon the character of the material to be operated upon and upon the character of seam desired, in general it may be said in regard to adjustments

of the members 30 and 40 to produce a given character of seam, that when soft material or material with a soft, a loose or a ragged edge is to be operated upon, the wall 32 is usually best set closer to the needle than is desirable when material to be operated upon is hard or has a firm and regular or finished edge. In the case of the member 40, when soft material or material with a soft, a loose or a ragged edge is to be operated upon, the wall 45 is usually set at a greater distance to the right of the plane in which the wall 32 lies than is desirable when material to be operated upon is hard or has a firm, regular or finished edge.

Having thus set forth a practical embodiment and an application of the principle of my invention, what I claim and desire to secure by Letters Patent of the United States is:

In an overseaming machine including a throat plate and a presserfoot, the combination of a fabric engaging element adjustably supported by the presserfoot and provided with an edge inclined to the line of feed, a fabric edge engaging element adjustably secured to the throat plate and having a fabric engaging surface extending in parallelism with the inclined edge of the presserfoot supported element, an edge guide adjustably secured to the throat plate and means for positively maintaining parallelism of the said adjustable elements throughout their respective ranges of adjustment.

SAMUEL W. AVIS.
